**PROCESS FOR THE PREPARATION OF
CYCLOHEXYLETHYL ALCOHOL**

2 Claims. (Cl. 260—617)

This invention relates to a new process for the preparation of cyclohexylethyl alcohol, which product and its esters are employed in perfumes.

It is known to prepare cyclohexylethyl alcohol by catalytic hydrogenation of phenylethyl alcohol which, in turn, can be obtained by catalytic hydrogenation of 1,2-epoxyphenylethane.

It follows that it would be advantageous to devise a method whereby cyclohexylethyl alcohol could be obtained in one operation, that is by a single hydrogenation of 1,2-epoxyphenylethane. In the first phase, i.e. the reduction of an epoxy group to an hydroxy group, good yields are obtained by operating, for example, with Raney nickel at low temperatures. The second phase, i.e. hydrogenation of the aromatic nucleus, requires more vigorous operating conditions. Hydrogenation with 6% by weight of Raney nickel at 200° C. under 210 atmospheres pressure has previously been described and under these conditions the yield of cyclohexylethyl alcohol is only 53%. A quantitative yield has been obtained, however, by operating at low temperatures, i.e. 25–30° C., but in order to obtain this result it has been necessary to employ 150% by weight of Raney nickel and a reaction period of 96 hours, which conditions render the industrial application of this process impracticable. In view of the present state of knowledge in the art, therefore, there would seem a priori to be very little chance of exceeding a yield of 50% in an industrial process for the production of cyclohexylethyl alcohol by combining the aforesaid two hydrogenation phases. Moreover, it has been observed that if 1,2-epoxyphenylethane is hydrogenated at 130–140° C. and under pressure in the presence of Raney nickel, two side reactions take place: polymerisation of the 1,2-epoxyphenylethane, and formation of ethylcyclohexane, both of which lower the yield of cyclohexylethyl alcohol.

According to the present invention there is provided a process for the production of cyclohexylethyl alcohol in excellent yields, which comprises introducing gradually 1,2-epoxyphenylethane into a suspension of a hydrogenation catalyst in an inert liquid medium at a temperature from 100° to 200° C. and under 50 to 300 atmospheres of hydrogen.

In order to obtain the higher yields in the foregoing process, it is desirable that the speed of introduction of the epoxyphenylethane should be controlled so that its proportion in the reaction vessel remains as low as possible throughout the hydrogenation, thus avoiding as far as possible the formation of by-products.

Suitable catalysts are those capable of facilitating the hydrogenation of the aromatic nucleus, for example, Raney nickel, Raney cobalt and supported ruthenium. The inert liquid medium should be a liquid inert to the conditions of the reaction, for example, methanol, ethanol or the hydrogenation product itself, i.e. cyclohexylethyl alcohol. The quantity of catalyst which should be employed depends upon its activity. Thus, supported ruthenium (e.g. on calcium carbonate or alumina) can effec-

2

tively be employed in a proportion as small as 0.1% by weight of ruthenium calculated on the total quantity of 1,2-epoxyphenylethane introduced. In the case of Raney nickel, a quantity corresponding to 1% by weight may be employed, but it is preferable to use 5–10%. After the reaction, the nickel can be recovered and used again for a subsequent hydrogenation, if desired after the addition of a small quantity of fresh catalyst. The nickel may be alloyed with small quantities of activator metals, such as iron or chromium.

The preferred hydrogenation temperatures range from 130° to 150° C. and the preferred pressures range from 80 to 120 atmospheres.

The following example will serve to illustrate the invention.

Example

Into a 3.6 litre autoclave provided with a rotating-frame agitator are introduced 100 g. of Raney nickel in suspension in 200 ml. of ethanol. The air in the autoclave is replaced by nitrogen, and then by hydrogen, after which 50 atmospheres of hydrogen is established at 25° C. On heating with agitation, the pressure rises. When the temperature reaches 140° C. and the pressure is 100 atmospheres 1,2-epoxyphenylethane is pumped in. The pressure rapidly falls to 80 atmospheres. Hydrogen is introduced to restore the pressure of 100 atmospheres. The pressure repeatedly falls to 80 atmospheres and each time it is restored to 100 atmospheres. The temperature is maintained at 140° C. by slight heating.

1000 g. of the epoxyphenylethane is injected during 3 hours and the pressure drops from 100 to 80 atmospheres and is restored to 100 atmospheres 15 times. The hydrogenation is continued for a further 3 hours 40 minutes at 140° C. until the absorption of hydrogen ceases, but during this latter period the pressure drops from 100 to 80 atmospheres and is restored only 3 times and on the fourth drop settles at 95 atmospheres.

After cooling and filtering off the catalyst, the following are separated by distillation: 125 g. of ethylcyclohexane; 806 g. of cyclohexylethyl alcohol, boiling at 106° C. at 19 mm. Hg; and 20 g. of residues (consisting mainly of polymers of epoxyphenylethane). The yield of cyclohexylethyl alcohol is 75.5% based on the weight of the epoxyphenylethane.

If, instead of the epoxyphenylethane being progressively introduced over a period of 3 hours, the same quantity is introduced all at once, then, after hydrogenating for 8 hours 30 minutes (all other conditions being the same) the following are separated by distillation: 372 g. of ethylcyclohexane; 484 g. of cyclohexylethyl alcohol; and 67 g. of residues. The yield of cyclohexylethyl alcohol in this instance is therefore only 45% based on the weight of the epoxyphenylethane.

We claim:

1. A process for the production of cyclohexylethyl alcohol which comprises gradually introducing 1,2-epoxyphenylethane into a suspension of a hydrogenation catalyst selected from the class consisting of Raney nickel, Raney cobalt and supported ruthenium in an inert liquid medium selected from the class consisting of methanol, ethanol and cyclohexylethyl alcohol, at a temperature from 100° to 200° C. and under 50 to 300 atmospheres of hydrogen, the rate of addition of the 1,2-epoxyphenylethane being such that the proportion thereof in the suspension is maintained as low as possible throughout the hydrogenation.
- 60 2. A process according to claim 1 wherein the hydro-

genation is effected at a temperature from 130 to 150° C.
and under 80 to 120 atmospheres of hydrogen.
